United States Patent Office

Des. 180,893
Patented Sept. 3, 1957

180,893

MOBILE MACHINE SHOP

Kibbey W. Couse, Newark, N. J.

Application May 10, 1956, Serial No. 41,429

Term of patent 14 years

(Cl. D14—3)

Des. 180,893

PAGE 2

Des. 180,893

Figure 1 is a perspective view, taken from the rear, and showing the mobile machine shop with the sides closed;

The essential features of my design reside in the portions shown in full lines.

I claim:

The ornamental design for a mobile machine shop, as shown and described.
